APPARATUS FOR BURNING LIQUID FUEL

Rallston M. Sherman, Glastonbury, Conn., assignor to The Silent Glow Oil Burner Corporation, Hartford, Conn., a corporation of Connecticut

Application March 29, 1934, Serial No. 717,967

5 Claims. (Cl. 158—76)

This invention relates to apparatus for burning liquid fuel (herein referred to for description as oil) and deals more particularly with burners of the so-called gun type. The invention has, among 5 other objects, the improvement of conditions of combustion pertaining to this type of burner, to increase the efficiency of such burners by reducing the power required for effectively burning fuel supplied at any given rate, and to simplify the 10 construction by reducing expense of manufacture and rendering the burner conveniently accessible after installation for purposes of cleaning, repair or readjustment.

In burners of the common form of so-called 15 "gun" type, liquid fuel is delivered under relatively high pressure to a nozzle, from which it is discharged without premixture with air through a relatively small nozzle into the combustion chamber of a furnace in the form of an expanding 20 cone-shaped spray of finely atomized oil. To provide a combustible mixture, air is discharged into the combustion chamber usually under the forced draft of a fan or blower, and through a conduit surrounding the nozzle and opening into 25 the combustion chamber, the latter being otherwise sealed off so that substantially the entire air supply available for combustion is delivered through such conduit about the nozzle and is intended to intermingle with the atomized oil.

30 In an attempt to enforce the intermingling of the atomized oil spray and the air discharged from the mouth of the conduit, devices have been employed designed to impart a helical or rotary movement to the air passing through 35 the conduit for the purpose of securing more intimate intermingling of the air and the oil spray. Such devices, however, have failed to produce the desired type of flame, which should be a fat, bushy, bright, smokeless flame, evidencing 40 complete combustion, and having a firm, stable, well defined and unwavering position. This I have discovered is due to the failure to so control the progressively and helically moving body of air on its emergence or release into the combustion chamber from the mouth of the conduit, and to so relate it to the expanding oil spray, that there shall be the required coincidence of movement and position between the released air and oil spray. If the dispersion of air to the combustion 45 chamber is so out of coincidence with the dispersion of the oil spray that a substantial amount of the free air required for combustion is discharged into the combustion chamber outside of the air spray, there results an undesirable 50

thin, torch-like flame with smoky ends. If the air dispersion is such that there is a discharge of a substantial amount of free oil outside of the air stream, there results an irregular and generally smoky flame. In either case, the flame has no 5 stable or well defined position, but is subject to a wavering or flickering action, this being particularly noticeable in the fluctuating position of the point where the flame is initiated ahead of the nozzle.

10 Where devices for imparting the rotary movement to the air have assumed the common form of fixed, broad, helical blades of relatively sharp pitch, mounted on and radiating from the centrally positioned nozzle pipe, they have not only 15 impeded the passage of air, increasing the power required for operating the burner, but have created an air turbulence destroying in part the true rotary movement of the air mass and leading to a dispersion of the air in the combustion chamber. 20 which tends to aggravate the absence of coincidence referred to.

The present invention has, among other objects, 25 imparting to the air mass traveling through the tubular conduit a helical or rotary movement under high momentum and the control of such helically moving mass of air on emergence into the combustion chamber with relation to an expanding cone-like oil spray, such that there is 30 established the required coincidence between the air and the oil spray when released in the combustion chamber, and the desired fat, bushy, steady flame is produced.

35 This and other objects of the invention will be best understood by reference to the following description when taken in connection with the accompanying illustration, while its scope will be more particularly pointed out in the appended claims.

40 In the drawings:

Fig. 1 is a front view of a burner embodying one form of the invention and looking back from the mouth of the burner nozzle;

Fig. 2 is a cross-sectional elevation of the conduit on the line 2—2 of Fig. 3, looking in the direction of the arrow;

Fig. 3 is a detail in cross-sectional elevation showing the forward portion of the tubular conduit;

Fig. 4 is a sectional elevation taken through the upper one of the two separable parts of the casing, showing such part removed;

Fig. 5 is a side elevation of the lower one of the two separable parts of the casing, showing 55

the fan impeller and other parts exposed by the removal of the upper separable part;

Fig. 6 is a side elevation of the burner shown in Fig. 1;

Fig. 7 is a plan view, partly broken away, showing the upper separable part of the casing removed; and

Fig. 8 is a sectional elevation of the front end of the tubular conduit, illustrating diagrammatically the combined action of the air and oil on emergence into the combustion chamber.

Referring to the embodiment of the invention here submitted for illustrative purposes, the burner is equipped (Figs. 5 and 7) with a rotary air impeller 11 having a central air intake and of the so-called Sirocco type. The impeller is mounted on a driving shaft 13 and comprises a disk 15 and a spaced opposed annular plate 17, with interconnecting multiple vanes or blades. On one side of the impeller and connected to the driving shaft 13 is mounted the electric driving motor 19 (Fig. 1), and on its opposite side and connected to the prolonged end of the driving shaft is the oil pump 21.

The impeller is contained within a housing 22, the upper part of which is of a generally cylindrical form, having its end wall or head facing the motor closed except for the opening through which the driving shaft extends, and the opposite side or end wall facing the pump providing an air admission opening 23 aligned with the opening of the annular plate 17 of the impeller. The amount of air admitted through the air admission opening is controlled by a disk-shaped shutter 25 (Fig. 1) which may be adjusted to a fixed position after the burner has been installed and its air requirements determined.

The impeller, which rotates in the direction of the arrow shown in Fig. 5, is mounted in eccentric relation to the peripheral walls of the housing 22, so that the clearance between such walls and the impeller is at a minimum at the point designated 27 in Figs. 4 and 6 (which may be termed the point of air registry), but gradually increases from that point to the air discharge portion of the housing at the bottom thereof. At the bottom or air discharge portion of the housing, the latter merges into a prolonged, straight, cylindrical, tubular air conduit member 29 having an open mouth at its forward end and extending in a general direction at right angles to the axis of rotation of the impeller and in a tangential relation to the discharge portion of the housing, so that the mass of air is urged in a straight line direction from the impeller to the mouth of the conduit without other obstruction than is offered by the parts contained in the conduit and hereinafter described.

Positioned axially within the conduit is an oil delivery pipe 31, terminating just short of the conduit mouth in a nozzle 33, and entering the conduit at one side at 35, where it has external connection to the oil supply pipe 37 extending to the discharge side of the pump 21, the supply pipe 39 for the pump being connected to any suitable source of supply (not shown), such as a main storage tank. The usual accessories, such as reducing valves, strainers, etc., are omitted for the sake of simplicity. Liquid oil without premixture with air is supplied by the pump to the nozzle at a relatively high pressure, as between 80 and 135 pounds and preferably within the neighborhood of 100 pounds per square inch, so that a high pressure mechanical atomization is produced at the nozzle, the liquid oil being

discharged therefrom in the form of a cone-shaped spray subtending an angle which may vary according to the type of nozzle employed, but which is usually between 45 and 80 degrees.

To ignite the commingled oil and air, one or more sparking electrodes 41 (herein two in number) are employed positioned in advance of the nozzle and connected each to a conductor 43, the latter being mounted in rigid, non-conducting sleeves 45 of porcelain or other like insulating material, the conductors entering the conduit through the bottom walls thereof at the points designated 47 in Figs. 6 and 7.

The motor rests on and is secured to a plate or shelf 49, and the pump rests on and is secured to a similar plate 51, both of which may be formed integrally with the impeller housing. Lugs 53, 55, 57 and 59, depending respectively from the motor plate 49, pump plate 51, impeller housing 22 and the conduit 29, provide means for attaching the burner to supporting legs or other supporting means when the burner is installed. On the installation of the burner, the forward end of the conduit is entered into and sealed within the walls 61 (Fig. 7) of the combustion chamber of the furnace, the open mouth of the conduit terminating preferably substantially flush with the inner walls of the combustion chamber, and the combustion chamber being sealed against any substantial admission of air other than that delivered through the conduit, so that substantially the entire air supply for combustion is delivered through and released from the open mouth of the conduit about the liquid oil spray delivered from the nozzle 33.

To maintain the nozzle in central position and the electrodes in fixed relation to the nozzle, a support 63 is provided in the forward end of the conduit (Figs. 2 and 3), and to reduce to a minimum the obstruction to air flow, such support is formed by bending up three pieces of thin sheet-metal which are screwed or clamped together about the sleeves 45 and the oil pipe 31, thereby providing a three-point sheet-metal support presented edgewise to the air flow and fitting loosely against the inner walls of the conduit.

After the burner has been installed occasional inspection of the nozzle and electrode connections may be required. Continued use also tends to the accumulation of dirt and dust on the blades of the impeller, reducing its efficiency and affecting the combustion by reducing the amount of air which should be supplied. As a means for providing instant access both to the impeller and to the nozzle and electrode connections, and at the same time as a means for materially simplifying the construction and reducing the cost of manufacture, I have formed the entire casing for the enclosed burner parts out of two interfitting but separable castings. Such casing comprises both the impeller housing and the tubular conduit, and with these also, in the illustrated embodiment of the invention, it additionally comprises the supporting parts for the motor and pump extending laterally from the impeller housing.

As shown in the drawings, the casing comprises a lower casting (Figs. 5 and 7) which includes substantially the lower half 22a of the impeller housing 22 (with the attached plates 49 and 51), the entire forward part 29a of the tubular conduit unbroken and intact where it passes through the combustion chamber walls, and substantially the lower half of the intermediate portion 29b of said conduit. Such casing further comprises an in-

terfiting and separable upper casting (Fig. 4) which is removable as a single piece, and includes substantially the upper or companion half 22^b of the impeller housing, carrying the point 21 of air registry and the upper or companion half 29^c of said intermediate portion of the conduit. The upper separable part of the casing is provided (Fig. 4) with a curved or flanged front wall 65, the bottom wall 67 and the back wall 10 69 adapted to lie and fit over the opposed mating walls of the lower part. A small depending lug 71 on the back wall 69 and a similar lug 73 on the bottom wall 67 at each opposite side of the portion 29^c provide each a threaded seat for a 15 single set screw, so that, when applied in place, the upper portion may be fastened securely but may be instantly removed after loosening the three set screws.

It will be observed that the separation of the 20 two parts is along a horizontal plane in the impeller housing, intersecting the axis of the impeller, and a horizontal plane coinciding substantially with the axis of the conduit and along an intermediate plane extending diagonally from 25 the axis of the impeller to the point of the lateral entrance of the oil nozzle pipe, the connection of the latter, however, being left intact in the lower one of the two separable parts.

The result is that the entire casing and support for the burner parts are produced from two 30 relatively simple castings, avoiding the necessity of the careful and expensive machine work usually required, and, after the burner is installed, all working parts of the burner within the casing 35 (as indicated in Figs. 5 and 7) may be instantly opened up for inspection, cleaning, repair or adjustment by merely loosening and lifting away the single separable upper part of the casing.

Features relating to the described construction 40 of the housing and the tubular air conduit are the subject of my divisional application, Serial No. 43,238, filed Oct. 2, 1935.

Referring now to the features bearing more 45 directly on the improvement in conditions of combustion, I have found that it is not only necessary to bring the air into coincident relation with the oil spray, but that for such coincidence and to properly control the air dispersion on release into the combustion chamber it is necessary 50 that the air leave the mouth of the conduit with the air particles traveling helically under high momentum, with an absence of any substantial irregular turbulence.

For this purpose means are employed for progressively impressing on the body of air forced 55 through the conduit a rotary motion, such means comprising (Figs. 3 and 8) a series of helically disposed ribs or vanes 75 (herein eight in number) extending inwardly from the inner walls of the forward part 29^a of the tubular conduit and 60 extending back from the mouth of the conduit through the cylindrical and uncontracted portion thereof for nearly half the length of the conduit.

These ribs are of relatively low or flat pitch, but, if desired, the pitch may progressively increase or become sharper from the impeller end of 65 the conduit toward the mouth thereof. The ribs are of relatively small height, but may progressively increase in height toward the conduit mouth, or preferably (as shown in Figs. 2 and 8) may remain of the same height for the major portion of their length and be sharply and materially increased in height (as indicated at 70 75^a) near the mouth of the conduit, such increase

beginning, however, a substantial distance back of the nozzle.

As shown in Fig. 8, which, in the Bristol board drawing accompanying the application, is a full size cross-section of the forward end of a conduit 5 embodied in an illustrative example of the invention, the mouth of the conduit is sharply contracted and the cylindrical interior terminates thereat in an inwardly tapered wall 77 inclined at a well defined angle. The ribs extend to the edge 10 of the conduit mouth and so increase in height that their inner edges coincide with the periphery of the conduit mouth, the conduit abruptly terminating thereat, so that the air has impressed upon it the full rotating effect of the ribs up to 15 the time of its release, such rotating effect reaching a maximum before it encounters any contraction in the conduit. The air therefore emerges into the combustion chamber as a progressively moving mass rotating under a high momentum and without substantial interfering turbulence.

As a numerical example, the specific construction illustrated in Figs. 3 and 8 may be instanced. There, the ribs have a length of approximately 8 25 inches, the conduit having an inside diameter of 3½ inches, and the pitch of the ribs at the conduit mouth is at the rate of one turn in 32 inches. That pitch of the ribs, if desired, may be gradually decreased or flattened toward their opposite ends until a pitch at the rate of one turn in 45 or 60 inches is reached, or the pitch may remain unchanged throughout their length. In such specific example, the ribs may be about 1/8 30 of an inch in height for the major portion of their length, reaching a height at 75^a adjacent the conduit mouth of approximately 3/8 of an inch, the mouth of the conduit being contracted to an inside diameter of 2 5/8 inches and the angle of the tapered wall 77 over and in contact with which 35 the air is discharged being approximately 45 degrees.

Since a straight cylindrical conduit is provided 40 extending back from its mouth in tangential relation to the discharge portion of the impeller housing, a substantially straight-way and unimpeded passage is presented to the air from the point where it is delivered by the impeller to the point where it is released from the conduit. As soon 45 as the ribs are encountered the advancing movement of the air under the action of the impeller is converted in part into a rotary mass movement. The helical ribs, extending as they do well back into the uncontracted part of the cylindrical conduit, effect at the beginning a slow movement of 50 rotation which progressively increases in intensity until the air reaches the mouth of the conduit where such rotating effect is at a maximum, the result being that with a minimum expenditure of power at the impeller a high momentum, rotary 55 movement of the entire mass of air is obtained at the point of air emergence without the production of interfering air turbulences.

This provides for a controlled and well defined 60 emergence of the air into the combustion chamber, which may be idealistically represented in Fig. 8. The entire air mass rotating under high momentum, on reaching the end of the conduit, 65 encounters the tapered wall 77 by means of which 70 it is caused to contract so that it becomes in effect, and emerges from the contracted mouth as, a contracting helix of progressively moving air. This effect persists for some distance in front 75 of the mouth of the conduit, the air helix con-

tinuing to contract until a point (such as indicated at 79 in Fig. 8) is reached where further contraction ceases and it tends to become an expanding helix of advancing air.

- 5 To properly coordinate with the oil spray this rotating and progressively moving air mass, which first contracts and then tends to expand, the oil nozzle 33 is so positioned that the periphery of the cone-shaped spray will be brought into 10 substantially coincident and tangential relation to the periphery of the helical air mass at or about the point 79 where the latter begins to expand.

The result is that from this point on each particle of air (comprising substantially all the air supplied for combustion) has a movement which is compounded of a rotary movement cutting transversely across the path of the oil particles comprising the spray and a linear progressive 20 movement which closely coincides in direction with the linear progressive movement of the particles comprising the oil spray.

After a point is reached approximating the point of coincidence 79, there follows substantially 25 no tendency for the dispersion of oil particles outside of the enveloping and expanding air helix, so that a smoky flame due to this cause is eliminated, and there is substantially no tendency for the dispersion of any substantial amount 30 of air required for combustion outside of the expanding cone of oil spray so that the tendency to form a thin torch-like flame along the axis of the cone is also prevented. The result is the production of a cone-shaped oil spray up to the point 79, 35 substantially as shown in Fig. 7 (which can readily be observed in the combustion chamber), beyond which, and beginning with a fixed, stable point or zone coinciding substantially with the point of coincidence, there occurs a bright, fat, 40 bushy and well defined smokeless flame having an unwavering and well defined position.

It is important that the nozzle mouth be positioned so as to secure the described coincidence of air mass and oil spray, and such position will 45 depend in part upon the angle subtended by the spray and in part upon the velocity of the air. In the specific example offered for illustration, the nozzle has a mouth corresponding to the diameter of a No. 76 drill, or approximately .020 50 inch, designed to be used with an oil supply under approximately 100 pounds of pressure, and with an air supply delivered through the described conduit and conduit mouth adjusted to burn approximately three gallons of oil per hour. With 55 a nozzle having a mouth of the dimensions indicated and working under the conditions described, a cone-shaped spray will be produced having an angle of dispersion approximately 45 degrees. This nozzle is positioned approximately $\frac{1}{8}$ of an 60 inch back of the conduit mouth, thus bringing the oil spray and rotary air mass into such a relation of approximate coincidence that the results described are secured.

If a nozzle is employed forming a wider angle 65 of oil spray, the nozzle should be advanced, and if it forms a sharper angle it should be retracted. In the illustrative example given, if a nozzle or pressure is employed so that the angle subtended by the oil spray approximates 60 degrees, the 70 nozzle should be advanced by about $\frac{1}{8}$ of an inch so as to be positioned about $\frac{3}{4}$ of an inch back from the conduit mouth.

The position of the oil nozzle indicated in the 75 foregoing numerical examples is with reference

to an air velocity represented by a static pressure in the air conduit of approximately .04 inch of water.

With the described form and dimensions of conduit and conduit mouth, if the air velocity is 5 diminished so that the air helix continues to contract only for a lesser distance from the mouth of the conduit the nozzle should be retracted, and if such air velocity is increased it should be advanced. Since the air supply and velocity may be 10 subject to some slight adjustment when the burner is first installed, provision is made for the adjustment of the nozzle 33 on the nozzle pipe 31, or an adjustment provided in the nozzle pipe itself, to afford the relatively small range of 15 nozzle adjustment indicated by the foregoing.

While I have herein shown for the purposes of illustration one specific embodiment of the invention, it is to be understood that the dimensional examples given, as well as the details of construction shown or referred to, are for illustration only, and that wide variations may be made in the details and features of construction and the relative arrangement of parts, all without departing from the spirit of the invention. 25

I claim:

1. For association with and as substantially the sole fuel and air source for a combustion chamber, a liquid fuel burner comprising a cylindrical air conduit having a contracted mouth 30 and extending rearwardly therefrom for a substantial distance to provide a straight-way passage for air therethrough, an impeller arranged to force air through said conduit, a spray nozzle axially located in said conduit near but rearward 35 of the contracted mouth thereof and means for supplying liquid fuel under pressure to said nozzle, said nozzle being adapted to provide a high-pressure mechanically atomized cone-shaped spray discharged through the mouth of said conduit, and means comprising angularly disposed elements on the inner wall of said conduit extending rearwardly for a substantial distance behind said nozzle and arranged to impart a high-momentum rotary movement to air moving through 40 said conduit before it passes through the contracted mouth so as to cause vortical motion of air discharged through said mouth.

2. A liquid fuel burner comprising an air impeller, a tubular air conduit having a contracted 50 mouth and arranged to receive air from said impeller under pressure and discharge the same through the mouth, a spray nozzle having an orifice formed to produce a cone-shaped spray of fuel and axially positioned in said conduit near 55 the mouth thereof to discharge said spray cone from said mouth, means for supplying liquid fuel under pressure to said nozzle, prolonged helically disposed vanes of relatively flat pitch projecting inwardly part way across the conduit from the 60 inner wall of the conduit and extending lengthwise of the same from a position ahead of said nozzle for a substantial distance rearward of said nozzle and adapted to impart to air passing through said conduit a high momentum, helical, 65 non-turbulent movement gradually accelerated to the conduit mouth, thereby to cause the body of advancing air to contract on emergence and then expand into substantial coincidence with said spray cone.

3. A liquid fuel burner according to claim 2 in which said vanes have a pitch of less than 45° and extend rearwardly from a point adjacent the mouth of the conduit for a distance not less than the internal diameter of the conduit. 73

4. For association with and as substantially the sole fuel and air source for a combustion chamber, a liquid fuel burner comprising a substantially straight cylindrical air conduit having a contracted mouth presenting a tapered wall inclined at a substantial angle, an impeller arranged to force air through said conduit, a spray nozzle axially located in said conduit near but rearward of the contracted mouth thereof and means for supplying liquid fuel under pressure and unmixed with air to said nozzle, adapted to produce a high-pressure mechanically atomized cone-shaped spray discharging through the mouth of said conduit, and helically disposed ribs on the inner wall of said conduit extending rearwardly from the mouth for a substantial distance behind the said nozzle and having an increasing pitch toward the mouth, said ribs being adapted to produce a vortical motion of air discharged through the conduit mouth.
5. For association with and as substantially the sole fuel and air source for a combustion chamber, a liquid fuel burner comprising a cylindrical air conduit having a contracted mouth and extending rearwardly therefrom for a substantial distance to provide a straight-way passage for air therethrough, an impeller arranged to force air through said conduit, a spray nozzle axially located in said conduit near but rearward of the contracted mouth thereof and means for supplying liquid fuel under pressure and unmixed with air to said nozzle, adapted to produce a high-pressure mechanically atomized cone-shaped spray discharged through the mouth of said conduit, and helically disposed ribs on the inner wall of said conduit extending rearwardly from the mouth for a substantial distance behind said nozzle and having an increasing height at their forward ends for imparting a high-momentum rotary movement to air moving through said conduit before it passes through the contracted mouth, thereby producing a vortical motion of air discharged through said mouth.

RAILSTON M. SHERMAN.
